Attorney

UNITED STATES PATENT OFFICE.

HENRY OTTO MESSNER, OF GLENDALE, NEW YORK.

STOVE ATTACHMENT FOR GAS-BURNERS.

1,286,706.

Specification of Letters Patent.

Patented Dec. 3, 1918.

Application filed June 30, 1917. Serial No. 177,923.

To all whom it may concern:

Be it known that I, HENRY OTTO MESSNER, a citizen of the United States, and resident of Glendale, in the county of Queens and State of New York, have invented certain new and useful Improvements in Stove Attachments for Gas-Burners, of which the following is a specification.

This invention relates to new and useful improvements in gas stoves, and the primary object of the invention is to provide a small and compact type of gas stove, which is adapted to be applied to the conventional type of gas burners, so as to quickly heat or cook in cases of emergency, or where it is not desirable or convenient to use a larger stove.

Another object of the invention is to provide a simple and efficient gas stove attachment for burners which may be easily and quickly applied thereto, the said stove having its various parts detachable, so that the stove may be thoroughly cleaned. This type of gas stove is applied to the gas burner without employment of the small flexible tube such as is ordinarily used for this general type of devices.

Another object of the invention is to provide a device of this character, which is easily and simply constructed, inexpensive to manufacture, and one which will be very efficient in operation.

With these and numerous other objects in view, my invention consists of the novel features of construction, combination and arrangement of parts which will be herein referred to and more particularly pointed out in the specification and claim.

In the accompanying drawings:

Figure 1 is a vertical section through the gas stove; and

Fig. 2 is a top plan view thereof.

In describing my invention, I shall refer to the drawings in which similar reference characters will designate corresponding parts throughout the several views. The numeral 1 designates the conventional type of upright burner standard having its upper edge externally threaded as shown at 2.

The burner stove comprises a body portion 3, that is formed in two parts, the lower part 4 thereof having a centrally disposed aperture, internally threaded and adapted for engagement with the externally threaded upper end of the gas standard 1. This bottom portion of the body 3 has an upwardly projecting flange formed on its outer

edge, provided with screw threads 5 on the outer surface thereof adjacent the top. The upper section 6 of the body of the stove is slightly larger than the lower section 4, and is provided with a plurality of spaced apertures 7 therein that are adjacent the marginal edge of the same. This upper section 6 is provided with a downwardly projecting internally threaded flange 8 adapted to engage the screw thread 5 on the outer sides of the upwardly projecting flange of the lower section.

The top section 6 is provided with a centrally disposed internally threaded aperture 9 therein, adapted to receive the lower end of a standard 10, that is externally threaded so as to cooperatively engage the threads of said aperture. Positioned on the upper end of the standard 10 which is likewise externally threaded is a top supporting plate designated by the numeral 14, which extends beyond the edge of the body portion 3 of the stove, said supporting plate being formed in two sections hingedly connected as shown at 15, and having arcuate elongated apertures 16 therein adjacent the marginal edge, and inner apertures 17 that also are arcuate, and which are disposed directly above the burner apertures 7 in the upper section 6 of the stove. This top plate 14 is connected to the upper end of the standard 10.

In operation, when the various parts of the stove attachment are assembled, as clearly shown in Fig. 1 of the drawings, the same is adapted to be applied to the conventional type of gas burner standard, it only being necessary to remove the tip therefrom, and screw the lower section of the body 3 of the stove into engagement with the top thereof. The gas will flow through the pipe 1 into the body portion 3, and hence out through the burner openings or apertures 7 in the top section thereof. At this point the gas is ignited, so as to heat the plate 14, the flame also passing through the apertures therein to thoroughly heat the receptacle or the like positioned thereon.

Owing to the fact that the various parts of this stove attachment are formed in sections, the body portion of the stove 3 being formed in two sections and the top plate being detachably connected therewith, said various parts of the stove are easily detached for cleaning. The body portion 3 is preferably cylindrical, and of a comparatively

small size, so that if it is desirable to leave the attachment on the burner, the same may when not in use be covered by a globe. The standard 10 will support the receptacle holding plate 14 a short distance above the burner portion of the stove, the exact distance being immaterial. This gas stove attachment may be very economically manufactured owing to the extreme simplicity of the construction, and the same may be quickly applied to a conventional type of gas burner. The attachment of the stove does not employ the usual flexible tube, which is very obnoxious and is not desirable for use in sick rooms.

From the above description taken in connection with the accompanying drawings, it is thought that a clear and comprehensive understanding of the construction, operation and advantages of my invention may be

had, and while I have shown and described the device as embodying a specific structure, I desire that it be understood that such changes may be made in said structure as do not depart from the spirit and scope of the invention as claimed.

Having fully described my invention what I claim as new and desire to secure by Letters Patent is:

A gas burner of the character described including a hollow body having a plurality of openings formed in the top thereof, a standard arranged concentrically of the top of said body, and a supporting plate composed of hingedly connected sections detachably engaged with said standard.

In testimony whereof I affix my signature hereto.

HENRY OTTO MESSNER.
